Herbert H. Fisher, 5106 Collins St.,
Panama City, Fla. 32401

Filed Mar. 13, 1967, Ser. No. 6,189

Term of patent 14 years

(Cl. D34—5)

FIG. 1 is a perspective view of a wheel roller for exercise and amusement embodying my new design;

FIG. 2 is a front elevational view of the wheel roller of FIG. 1;

FIG. 3 is a rear elevational view of the wheel roller of FIG. 1;

FIG. 4 is a side elevational view of the wheel roller of FIG. 1;

FIG. 5 is a top plan view of the wheel roller of FIG. 1, and

FIG. 6 is a perspective view of the wheel roller wherein three parallel plates are employed.

The broken lines showing of a wheel in FIGURES 3, 4, and 5 are for illustrative purposes only.

I claim:

The ornamental design for a wheel roller for exercise and amusement, substantially as shown and described.
